POURING SPOUT CONTAINER

Arthur G. Hopkins, Maspeth, N. Y., assignor to
 National Can Corporation, New York, N. Y.,
 a corporation of Delaware

Application February 27, 1940, Serial No. 320,997

6 Claims. (Cl. 221—11)

The present invention relates to a pouring spout container and has especial reference to the provision of a metallic container having an improved pouring spout structure mounted in an end wall thereof.

The prime object of my present invention resides in providing the dished end of metallic containers or cans with an improved pouring spout for dispensing liquid contents thereof, the pouring spout being movable between inoperative and operative positions, the spout in its inoperative position lying substantially wholly within the geometrical confines of the dished end and can body, and in its operative position having its pouring mouth extending freely from the can body. By means of this construction, the pouring spout when in its inoperative position is out of the way and permits the cans to be stacked and otherwise handled in the usual manner, and when in its operative position permits the contents to be dispensed from the can without any part thereof pouring over or flowing on to the can body. A correlative object of the invention pertains to constructing a pouring spout of this nature for and in combination with can body friction covers of the inset dished type.

Further objects of the invention include the provision of a pouring spout for cans which is exceedingly simple in structure and design, the pouring spout fashioned from a single piece of material being revolvably mounted directly in the container end wall in a suitably shaped integral part thereof; the provision of such a structure in which such end wall part is shaped to cause the spout to move from the confined inoperative position to the freely extending operative position; the provision of a pouring spout of this nature combined with a plug type of closure for the pouring opening, and the further provision of a revolvable pouring spout combined with a plug closure in which the pouring spout and closure are interrelated so that the plug tends to hold or lock the spout in its confined or inoperative position and preferably so that rotation of the spout to its operative position tends to lift the plug closure to open position.

To the accomplishment of the foregoing and such other objects as may hereinafter appear, the invention further consists in the structural combinations hereinafter sought to be defined in the claims and described more in detail hereinbelow in connection with the appended drawings, in which:

Figure 1 is a top plan view of a pouring spout container embodying the structure of the present

invention, the pouring spout being shown in its confined and inoperative position;

Figure 2 is a similar view thereof in which the pouring spout is shown in its extended operative position;

Figure 3 is an elevational view thereof shown on an enlarged scale with parts shown in section;

Figure 4 is a view of the plug closure used in this construction;

Figure 5 is a view thereof on an enlarged scale, taken in cross-section in the plane of the line 5—5 of Figure 1 and showing an interlocking relation between the spout body and the plug closure;

Figure 6 is a similar view thereof and showing the manner in which the rotation of the spout body lifts and loosens the plug closure;

Figure 7 is a view of a modified can structure with parts in section showing the spout structure embodied in the can end opposite to the filling end thereof;

Figure 8 is a view taken in cross-section of another form of the invention, showing a modified form of plug closure for the spout opening; and

Figure 9 is a top plan view of Figure 8.

Referring now more in detail to the drawings and having reference first to Figures 1 to 6 thereof, the pouring spout container of the invention comprises a metallic container 10 provided with an end wall 11 of dished formation, the said dished end wall being constructed to embody a pouring spout structure generally designated as 12. The pouring spout structure 12 and the dished end wall 11 are so designed and constructed that the pouring spout may be rotated from the inoperative position shown in Figures 1 and 3 of the drawings, in which position it lies substantially wholly within the geometrical confines of the dished end wall 11, to the extended position shown in Figure 2 of the drawings, in which position the mouth of the spout extends freely above and beyond the can body 10.

The dished end wall 11 in the form of the invention shown in Figures 1 to 6 of the drawings comprises a friction or plug cover of the inset type consisting of a marginal wall 13 and a depressed bottom wall 14, the marginal wall 13 terminating in the usual bead 15. The friction or plug cover is received by the annular end wall formation 16 which is double seamed to the can body 10 in the usual way to form the peripheral rim 17. When the spout structure is thus embodied in an inset dished friction cover, it will be

understood that when the spout is moved to its operative position as shown in Figure 2, the mouth, to project freely from the can body, must extend over and beyond both the cover bead 15 and the double seamed marginal rim 17.

The dished end wall 11 is provided with a pouring opening 18, and the material of the depressed bottom wall 14 thereof is shaped or formed at this pouring opening 18 to provide means for rotatably receiving the pouring spout 12 and for directing the same into the confining and extending positions when the spout is rotated. This is accomplished in a very simple way by shaping the metal of the said wall 14 at and around the pouring opening so as to provide or form a circular cam track 19 bounded by a circular bead 20. The cam track 19 (see Figure 3) lies at an angle to the plane of the depressed wall 14 of the dished end wall, the lowest point of the cam surface being near the center of the can body and the highest point being diametrically opposite, as clearly shown in Figure 3. The bead 20 defines the mouth of the pouring opening and the hollow of the bead defines a socket for rotatably receiving a part of the spout structure as will be presently described.

The pouring spout 12 is fashioned from a single sheet of material to provide a neck portion 21 and a mouth portion 22 extending from the neck portion. The neck portion 21 overlies the cam track 19 and is adapted to ride on this cam track when the spout is rotated between its inoperative and operative positions. This is most simply accomplished by the provision of a flange 23 in the bottom of the neck 21, which flange lies on the cam track 19 and in the hollow or crimp of the bead 20. By means of this simple construction, it will be seen that when the spout 12 is in or is moved to the inoperative position shown in Figures 1 and 3 of the drawings, the spout 12 is in a substantially horizontal position and lies wholly within the geometrical confines of the dished end 11 permitting normal container stacking, and that when the spout is rotated to the operative position shown in Figure 2 of the drawings, the neck flange 23 rotates in the bead socket 20 and rides upon the cam track 19 so that when the spout is in the operative Figure 2 position, the mouth thereof and particularly the lip 24 thereof extends freely above and beyond the can body parts; this latter is best illustrated in Figure 7 of the drawings. The mouth 22 of the spout is concavely shaped into channel form and the body edges may be suitably finished into the marginal bead 25.

This interrelation of the can body end wall and the spout structure enables the use of a plug type closure for closing and sealing the pouring opening. The bead 20 defines the means for receiving the plug closure, and the said plug closure, generally designated as 26, may comprise the plug body 27 removably receivable by the bead 20, and a flange part 28 arranged to overlie and engage the spout body and particularly the bead 25 thereof. The flange part 28 may be provided at diametric regions with the upset parts 29, 29 which, spaced from the spout bead 25, permit a coin or other implement to be inserted for lifting the plug closure to open position. The plug closure is also preferably provided with a skirt 30 depending from the flange 28 at one part thereof (see Figures 3 and 4), the bottom edge of this skirt being curved to conform to the channel curvature of that part of the spout mouth which is engaged by this skirt. By means of this con-

struction, the plug closure seals the spout structure in the region engaged by the closure, and the plug closure being fixedly held by the pouring mouth bead 20 tends, by the engagement between the said skirt 30 and the spout mouth, to hold and lock the spout against rotation. This latter is best shown in Figure 5 of the drawings. Also, this mating between the closure skirt 30 and the spout mouth 22 is such that when the spout 12 is rotated towards operative position, the skirt 30 is caused to ride up on the curved wall of the spout mouth, resulting in the plug closure being lifted towards open position, this being best shown in Figure 6 of the drawings wherein the spout 12 is shown moved from its inoperative position through an angle of 90° with the plug shown lifted partly to open condition. To return the plug closure to its sealing or closing position, the spout structure 12 must first be returned to its inoperative or confined position.

In Figure 7 of the drawings, the invention is shown applied to a container or can in which the inset friction cover used for filling a can is located at one end of the can, and in which the other end wall of the can is dished and embodies the pouring spout structure of the present invention. Thus in this modification, the can body 10 is provided at one end with the dish shaped end wall 11, which latter extends across the entire area of the can and is double seamed to the can body to produce the peripheral rim 17. This dished end wall and the pouring spout embodied therein otherwise have parts corresponding to those shown in Figures 1 to 6 of the drawings, which parts are indicated by similar and primed reference characters. This Figure 7 shows how the mouth 22 and particularly the lip 24 of the pouring spout 12 extends freely above and beyond the can parts so that the fluid contents of the can may be dispensed therefrom without any part of the fluid contents pouring over or flowing on to the can body. When the fluid contents consist of a sticky liquid such as syrup, it will be seen that the can body may thus be kept free of the liquid and clean. In this form of construction, the filling of the can is accomplished by providing the other end of the can body with the inset type of friction cover 31. Thus, for filling purposes, one end of the can is used, and for dispensing or discharging purposes, the spout structure at the other end of the can is used.

In Figures 8 and 9 of the drawings, I show a modified form of spout structure wherein the plug closure is constructed so as to completely cover the spout body. Otherwise, this modification of Figures 8 and 9 is the same as that depicted in Figures 1 to 6 of the drawings, and similar parts are designated by similar reference characters. The plug closure 32 of this construction comprises the plug body 33 receivable by the bead 20, the flange 34 which overlies and contacts the rear and part of the sides of the spout bead 25, and a tongue portion 35 extending forwardly of the plug body 33 and over the entire area of the spout mouth 22. The sides of the tongue portion 35 may be turned down as at 36 to cover the sides of the spout mouth 22, and the end of the tongue portion 37 may be turned down to cover the lip 24 of the spout mouth. With this construction, the plug closure in mating with the parts of the pouring spout effectively holds or locks the same against rotation. The closure is provided with the upset portions 38 for prying up purposes, whereby the closure

may be lifted to open the pouring opening and to permit the spout to be rotated to the operative position.

The structure and mode of use and the advantages of the pouring spout container of the present invention will, in the main, be fully apparent from the above detailed description thereof. By means of the constructional principles employed, a pouring spout of exceedingly simple design is produced having the functional features described. It will be apparent that changes may be made in the construction without departing from the essence of the invention defined in the following claims.

I claim:

1. A pouring spout container comprising a container provided with an end wall of dished formation, the said dished end wall consisting of a marginal side wall and a depressed bottom wall, a pouring opening in said bottom wall, and a cam track in said bottom wall around the said pouring opening, said cam track lying above and at an angle to the plane of said bottom wall; and a spout rotatably mounted on and lying above said depressed bottom wall, said spout having a neck portion which overlies the cam track and is adapted to ride thereon and having a mouth portion extending from said neck portion, the said spout being movable between a position lying wholly within said dished end to a position where the said mouth angularly extends upwardly and outwardly beyond the side wall of said dished end.

2. A pouring spout container comprising a container provided with an end wall of dished formation, the said dished end wall consisting of a marginal side wall and a depressed bottom wall, a pouring opening in said bottom wall, and a circular cam track around the pouring opening pressed up out of the metal of said bottom wall, said cam track lying above and at an angle to the plane of said bottom wall; and a spout rotatably mounted on and lying above said depressed bottom wall, said spout having a neck portion which overlies the cam track and is adapted to ride thereon and having a mouth portion extending from said neck portion, the said spout being movable between a horizontal position lying wholly within said dished end to an inclined position where the said mouth extends upwardly and outwardly beyond the side wall of said dished end.

3. In the pouring spout container of claim 1, a closure for the pouring opening comprising a

plug body for the opening and a flange engaging the body of the pouring spout.

4. A pouring spout container comprising a container provided with an end wall, part of the material of said end wall being shaped to form a circular cam track and a circular bead bounding the cam track, the bead defining the mouth of the pouring opening; a spout rotatably mounted on said wall, said spout comprising a neck portion overlying and adapted to ride on the cam track and a mouth portion extending from the neck portion; and a closure for said opening including a plug body engaged by said bead and a part engaging the spout mouth, the said engaging part and the spout mouth mating so that the spout is held thereby against rotation and so that rotation of the spout tends to lift the plug closure.

5. A pouring spout container comprising a container provided with an end wall, a bead formed in said wall defining a pouring opening, a cam track around said bead; a spout rotatably mounted on said end wall, said spout comprising a neck portion overlying and adapted to ride on the cam track and a mouth portion extending from the neck portion; and a closure for said opening including a plug body engaged by said bead and a flange engaging the spout mouth, the flange and spout mouth mating so that the spout is held thereby against rotation and so that rotation of the spout tends to lift the plug closure.

6. A pouring spout container comprising a container provided with an end wall of dished formation, the said dished end wall consisting of a marginal side wall and a depressed bottom wall, part of the material of said bottom wall being shaped to form a circular cam track and a circular bead bounding the cam track, the bead defining the mouth of a pouring opening and the hollow of the bead defining a socket; said cam track lying above and at an angle to the plane of said bottom wall; and a spout rotatably mounted on and lying above said depressed bottom wall, said spout having a neck portion which overlies the cam track and is adapted to ride thereon and having a mouth portion extending from said neck portion, the said neck portion having a part which rides on the cam track and rotates in the socket of said head, the said spout being movable between a position lying wholly within said dished end to a position where the said mouth angularly extends upwardly and outwardly beyond the side wall of said dished end.

ARTHUR G. HOPKINS.
